UNITED STATES PATENT OFFICE

ALFRED HEALD, OF PHILADELPHIA, PENNSYLVANIA, ASSIGNOR TO
McCALLUM, CREASE & SLOAN, OF SAME PLACE.

DESIGN FOR CARPET.

Specification forming part of Design No. 6,720, dated June 24, 1873; application filed June 6, 1873.

To all whom it may concern:

Be it known that I, ALFRED HEALD, of the city and county of Philadelphia, State of Pennsylvania, have invented a Design for a Carpet-Pattern, (H,) of which the following is a specification:

The entire groundwork of the pattern forming the subject of my design, which is clearly illustrated in the drawing, is separated into equal square or diamond-shaped spaces by ornamental bands or ribbons A, crossing each other at right angles, and the continuity of which is interrupted by small square figures a and diamond-shaped figures b. Within each

of the spaces thus formed is a medallion, B, of a character so clearly shown in the drawing as to render minute description unnecessary.

Irrespective of the colors employed, I claim—

The design for a carpet-pattern, substantially as described, and as represented in and by the accompanying drawing.

In testimony whereof I have signed my name to this specification in the presence of two subscribing witnesses.

Witnesses: ALFRED HEALD.

HUBERT HOWSON.
